W. R. BERRYMAN

SHUTTLE BOBBIN

Filed Nov. 11, 1921

William R. Berryman, INVENTOR
BY
Thomas H. Howe, ATTORNEY

UNITED STATES PATENT OFFICE.

WILLIAM R. BERRYMAN, OF BROOKLYN, NEW YORK.

SHUTTLE BOBBIN.

Application filed November 11, 1921. Serial No. 514,430.

To all whom it may concern:

Be it known that I, WILLIAM R. BERRYMAN, a citizen of the United States of America, residing at Brooklyn, county of Kings, 5 and State of New York, have invented new and useful Improvements in Shuttle Bobbins, of which the following is a specification.

This invention relates to the bobbins employed in the shuttles of sewing machines and the like. It is contemplated that it will be chiefly useful in connection with such applications, but is not limited thereto.

It is quite usual in placing the thread 15 upon the shuttle bobbin of an ordinary sewing machine to rotate the bobbin by suitable apparatus and so wind the thread thereon. It is desirable that this rewinding shall be avoided and that the spool of thread or twine 20 be inserted in the shuttle as it comes from the manufacturer without rewinding.

It is the main object of the invention, therefore, to provide a bobbin of which a cylindrical portion may be supplied to the 25 manufacturer and on which the thread or twine may be wound by him, which bobbin shall also comprise parts which may be added to the spool as it comes from the manufacturer to form the complete bobbin 30 adapted for insertion in the shuttle.

The spool employed by the thread and twine manufacturers is usually a hollow pasteboard cylinder upon which the thread 35 is wound and accordingly I prefer to make the hollow cylindrical or spool portion of the improved bobbin of such material. Such substances are, however, not suitable to form bearing surfaces as required on a bobbin in a shuttle; and it is therefore a further object of the invention to so construct the bobbin, utilizing the manufacturer's spool, that a more durable and accurate bearing surface 40 of the bobbin is provided than would be provided by the said spool.

Other and ancillary objects of the invention will appear hereinafter.

In the accompanying drawings which illustrate the invention—

Fig. 1 is a side elevation of a wound bobbin embodying the invention;

Fig. 2 is a side elevation, partly in section and partly broken away, of a shuttle having the improved bobbin mounted therein;

Fig. 3 is a perspective view of an end head 55 for the bobbin; and

Fig. 4 is a perspective view of the spool of the bobbin.

Referring to the drawings, the bobbin therein shown comprises a hollow cylindrical spool portion 1, preferably of pasteboard, 60 upon which the thread or twine 2 is wound in any of the well known ways of winding thread upon a spool. The shuttle 3 may be of any well known or suitable construction having a bobbin recess 4 into which projects 65 a shaft or spindle 5 whereon the bobbin is rotatably mounted.

The spool as it leaves the hands of the manufacturer comprises the cylindrical portion 1 with the thread or twine 2 wound thereon. The metal journal members 6 and 7 are then applied thereto when the bobbin may be inserted in the shuttle, the shaft 5 entering within the spool portion 1 and the journal members as shown in Fig. 2 when 70 the shuttle with the bobbin can be inserted in the sewing machine, the bobbin rotating upon the shaft 5 in the usual way. Each of the journal members comprises a side portion 8 from which extends a projection 9 75 adapted to fit rather tightly within the end of the tube portion 1, while the hole 10 extending entirely through the head is of a diameter such as to give a running fit about the shaft 5. Each journal member is a single integral 80 piece so that there is no danger of the side falling off as where the side and projection are separate pieces.

To prepare the spool as it comes from the manufacturer to be entered within the shuttle, the journal members 6 and 7 are put in place at either end by telescoping the projections 9 within the ends of the spool portion 1. The bobbin is then placed in position within the shuttle by entering the shaft 95 through the journal members and spool portion.

It will be seen by reference particularly to Fig. 2 that the spool portion 1 which is usually of material such that it has not suitable wear resisting properties or is adapted to accurately hold the bobbin in position, does not come in contact with the shaft 5, but the bearing surface for the bobbin is provided by the journal members which are 100 formed of harder and greater wear resisting material which can be fitted with sufficient accuracy to the shaft upon which the bobbin turns and will not deteriorate with undue rapidity in use. The material of the journal 105

members is preferably of some suitable metal such as brass but might be of hard fibre or other suitable substance.

While the invention has been illustrated in what is considered its best application it may have other embodiments without departing from its spirit and is not therefore limited to the structure shown in the drawings.

What I claim is:

- 5 10 The combination with a shuttle having a bobbin recess, and a bobbin supporting spindle in said recess, of a bobbin within said recess and mounted to rotate upon said spindle,

said bobbin comprising a hollow paper cylinder upon which the thread is wound and journal members telescoping within the ends of said cylinder, separable therefrom and provided with axial openings for the reception of the shaft, said shaft extending within said cylinder and openings, said 20 journal members being formed with thread retaining flanges.

In testimony whereof I have signed this specification this 10th day of November, 1921.

WILLIAM R. BERRYMAN.
